UNITED STATES PATENT OFFICE.

WRIGHT D. SMITH, OF DETROIT, MICHIGAN, ASSIGNOR TO THE HUYETTE & SMITH MANUFACTURING COMPANY, OF SAME PLACE.

STEAM-GENERATOR.

SPECIFICATION forming part of Letters Patent No. 487,300, dated December 6, 1892.

Application filed May 27, 1892. Serial No. 434,576. (No model.)

To all whom it may concern:

Be it known that I, WRIGHT D. SMITH, of Detroit, in the county of Wayne and State of Michigan, have invented a new and useful 5 Improvement in Steam-Generators, of which the following is a specification.

My invention relates to that class of steam-generators made up of coils of pipe arranged with a view to obtaining rapid general circulation through the pipes with a maximum exposure to heat and occupying a minimum of space.

This boiler is especially intended for use on vessels; and my object has been to provide for a free and continuous generation of steam under all conditions which are likely to occur on a vessel—as, for instance, when the vessel lists to one side or the other, so as to make a considerable difference in the level 20 of opposite points of the boiler, which are normally in the same horizontal plane.

In the drawings making part of this specification, Figure 1 is a perspective view of the boiler as the tubes would appear if the external jacket with which such boilers are inclosed should be entirely removed. Fig. 2 is a horizontal section showing the base of the boiler. Fig. 3 is a horizontal section taken near the top of the boiler through the feed-water heaters and receivers, and showing, also, the superheating steam-pipes. Fig. 4 is a rear end elevation. Fig. 5 is a front end elevation. Fig. 6 is a longitudinal central section through the center of the boiler from front to rear. Fig. 7 is a side elevation of the boiler.

The same letters are employed in all the figures in the indication of identical parts.

It must be understood that the figures show only the pipes which are on the inside of an inclosing jacket such as is commonly used in boilers of this class, but which is not shown in any of the drawings. It should also be understood that the boiler as constructed would be made up of a greater number of pipes of smaller relative diameter than those shown in the drawings. Such pipes will, however, be a mere multiplication of those which are shown, and they have been represented as farther apart than would be usual in working practice in order to avoid confus-

ion in their representation. In practice these pipes will be set as close to one another as can be done without impairing the free circulation of the heat around the tubes.

55

In describing the boiler I will follow the course of the water as it travels through the boiler, being converted into steam as it progresses, until finally the steam is drawn out through a steam-pipe leading to the engine. 60

Two feed-pipes A A' are shown most clearly in Fig. 3 as entering at the rear of the boiler and passing forward below the steam-drum and entering a transverse pipe B, as shown in Fig. 1 at A A', which there represent the 65

T's at the termination of the feed-water pipes. The pipe B is horizontal and extends entirely across the width of the boiler and terminates in the two drums C C'. These are the feed-water heaters and receivers by which the 70

feed-water is heated and stored in considerable quantities, so as to supply an adequate amount of water continuously, and so avoid those rapid variations in the level of the water, which are both troublesome and dangerous in the ordinary forms of tube boilers. To 75

This end these drums are placed over the coils and within the jacket, so that they may take up heat from the draft which has passed upward through the interstices between the coils 80

of pipe and which would otherwise be wasted. By this means they act as heaters, while their size and location at or near the water-level of the boiler fits them to act as reservoirs for maintaining a constant supply of water 85

throughout all the tubes below them. They are placed so as to lie immediately below the plane of the high-water line of the boiler and above the plane of the low-water line, so that 90

they are always at least partly filled with water, and as they lie on the top of the coils they are always able to supply water to the boiler.

At each side pipes D are placed, leading out of the middle of the length of the drum. At the bottom there are placed the connected 95

base-pipes E E' E² E³, quadrilateral in form and opening into one another, so as to afford a free circulation around the entire base. Inside of these base-pipes are placed the grate-bars F, the upper surfaces being in the plane 100 of the middle line of the base-pipes, which inclose them, and on either side of the horizon-

tal base-pipe E⁴, which extends from end to end of the boiler and is connected with the pipes E² E³. The pipe E² is not indispensable, and if not used then the pipe E⁴ would connect only with the rear pipe E³. These base-pipes surround and lie substantially in the plane of the grate-surface, and as they are connected to one another and by other pipes, to be hereinafter described, with the steam-drum there is formed a complete circulatory system through the pipes, steam-drum, and intermediate pipes. Along the crown of the side, central, and rear base-pipes are placed in near proximity to one another vertical pipes G G' G², which open out of the base-pipes and lead upward, forming, with the vertical pipes S, which open out of the back base-pipe E³, the sides and rear end of the fire-box, into which the fuel is introduced through doors in the front of the jacket in the ordinary manner. What may be called the "crown" of the fire-box is formed by a series of horizontal pipes running transversely and connected in the usual manner by T's I I' with the upper ends of the vertical pipes G G'. These pipes carry the water and steam which rise from the central vertical pipes G² and deliver them through the T's to the transverse coils K and K'. These coils respectively extend from the sides to about the middle of the boiler, where they are connected by return-bends in the usual manner, so as to travel in a zigzag path from side to middle and middle to side of the boiler until they terminate in the lower part of the longitudinal steam-drum L, which lies over the center of the boiler. Near the ends of the side base-pipes E and E' are short vertical pipes M, connected with coils N, which run along the side of the boiler immediately outside of the vertical tubes G and then around the corner angle and thence horizontally to the middle of the boiler opposite the end of the base-pipe E⁴, whence they are returned by means of return-bends in the opposite direction and again and again reversed until they pass above the tubes of the lower elbows connecting pipes D and pipes K, where they terminate in a vertical pipe O, (shown distinctly in Figs. 6 and 7,) which leads into the end of the back cross-drum P, which is connected by an elbow P' with an opening through the head of the steam-drum L.

Steam is taken out of the steam-drum at the top or near the top thereof by means of pipes Q, which are connected with the super-heating steam-pipes Q', which are within the hot-air chamber at the top of the jacket and are exposed to a temperature sufficient to dry the steam and prepare it for delivery to the cylinder of the engine through an extension of the pipe Q'. (Shown in Fig. 3, also in Figs. 6 and 7.)

The water which accumulates in the bottom of the steam-drum L is delivered therefrom through a central return water-pipe or drop water-leg R, leading from the middle of the

bottom of the boiler to the middle of the pipe E⁴. The pipes R and E⁴ are about of the same diameter—say for one hundred-horse-power boiler each four inches in diameter. This gives a free passage for the water that is drawn up into the steam-drum to flow out and return to the base-pipes, where it is mingled with the feed-water and restored to circulation through the connected system of pipes. The location of this pipe in the middle of the bottom of the steam-drum has the advantage derived from that position that as the vessel pitches in riding the waves and the water rushes from one end to the other of the steam-drum it will pass over the pipe R and will escape more freely than is the case with that common arrangement of return-pipes in pipe boilers where they are lead out of openings in the heads of the steam-drum, generally elevated above the shell, so that they cannot entirely drain the water from the drum.

There is still another set of pipes which connect the base-pipes with the steam-drum. Along the back base-pipe B³ is placed a series of vertical pipes S on the rear end of the fire-box, which extend upward and are connected, respectively, with the coil-pipes S', which run from rear to front and from front to rear between the transverse coils K and K', with which they are interlaced, as clearly shown in the drawings, and discharge into the back cross-drum P, entering the same at the side, as shown in Figs. 6 and 7. In front of the boiler, extending from the base-pipe to the steam-drum, is placed the ordinary water column T, provided with a water-indicator tube and a steam-gage. It will also be observed that the pipes and coils of pipes throughout this boiler are arranged in planes which are vertical and either longitudinal or transverse, so that they cross one another at right angles. The pipes H, H', K, K', and S' are laid on one another in series, the lower line of the coil-pipes S' resting directly on the transverse horizontal pipes H H'. The transverse pipe of the first coil K and K' lies upon S', and so on to the top. From this it results that the system of coils is supported directly upon the transverse horizontal pipes H H', which are supported at both ends upon the side vertical pipes G G' and the middle vertical pipes G², so that the whole structure rests upon this solid support and the pipes are not liable to sag, as is the case with that class of boilers in which the coils are supported only at one end. Each pipe that goes out of the base-tubes connects directly with another pipe in its own vertical plane, by which the steam and water passing through the vertical pipe is carried through its own appropriate conduit and delivered independently into the steam-drum L. From this arrangement it results, first, that in case of injury to any one of the pipes or its becoming stopped from any cause that single pipe may be plugged without in any way interfering with the free and entirely independent oper-

ation of all the other pipes, and, secondly, that as the coils are laid in vertical, longitudinal, and transverse planes, lying directly one on top of the other, there are vertical rectangular spaces left between them, forming minute flues permeating every portion of the system and leaving no exposure for the lodgment of ashes on the top surfaces of the pipes, as is liable to occur in that class of pipe boilers in which the tubes are not so arranged in vertical planes. The arrangement of the vertical pipes G G' G² forms an interior wall confining the fire-box at the sides and center, while the corresponding pipes S form the rear wall of the fire-chamber. Outside of these are placed the coil-pipes N, which receive whatever heat may pass through the spaces left between the vertical pipes. By this means the heat has to pass through two series of pipes and will be very largely taken up before it reaches the jacket, so that there will not be much loss of heat in that direction. The advantage that results from the use of the pipes running only half the width of the boiler and maintaining these pipes constantly on their own proper side until they deliver their water and steam mingled into the steam-drum is that one or the other set of these pipes will always be free for the transmission of steam, however much the vessel may list. Thus if it lists to starboard the port system of pipes will be left entirely free for the passage of steam toward the drum, the water running down to the system of pipes on the starboard side. Thus there is always a free circulation for the steam to the steam-drum, however much the vessel may list, either to starboard or port. As there will always be an active circulation of water or steam in these pipes, they are not liable to become overheated. In the case of boilers that are constructed with lateral coils running entirely across the boiler from side to side when the vessel lists to one side—say to starboard—the water will flow to the starboard side and the steam will be confined in the port ends, its escape being so impeded that the pipes are liable to become red-hot.

What I claim as my invention, and desire to secure by Letters Patent, is—

50 1. In combination with the base-pipes E E', E³, the vertical series of tubes G G' S, forming the sides and rear end of the fire-box, and the double series of coil-tubes N, receiving water through the tubes M and extending horizontally along the side and half-way along the back series of vertical tubes, thus forming a

double system of pipes around the sides and back end of the fire-box, substantially as set forth.

2. In combination with the base-pipes E, E', E³, and E⁴, the vertical series of tubes G, G', G², and S, forming the back end and partition of the fire-box, and a series of tubes H H', placed in horizontal plane and respectively connecting the side and partition vertical tubes at the upper end and forming the crown of the fire-box, substantially as set forth. 60

3. In combination with the base-pipes, vertical tubes forming the sides, end, and partition of the fire-box, the series of horizontal tubes H H', connecting the side and partition tubes, and the double series of coil-pipes K, K', and S', supported on the crown-pipes, substantially as set forth. 70

4. The double series of transverse coils K 75 K' and interlaced longitudinal coils S', arranged, respectively, in vertical planes and at right angles to one another and forming rectangular flues extending from the crown-tubes to the space above the boiler, substantially as set forth. 80

5. The combination of a series of transverse pipes H H', each connected at the ends and center with the base-pipes E, E', and E⁴ and with the independent transverse coils K 85 K', respectively discharging into the steam-drum on opposite sides thereof, substantially as set forth.

6. In combination with the receiver and feed-water heater placed over the coils of the boiler 90 between the high and low water lines and a feed-water pipe connected thereto, the base-pipes and a conduit for delivering water thereto from the former, substantially as set forth. 95

7. In combination with a connected system of base-pipes which inclose the grate-bars, the steam-drum and system of pipes leading from the former to the latter and a return or drop pipe opening out of the bottom of the steam-drum midway between its ends, passing down through the fire-box, and discharging into the central element E⁴ of the connected base-pipes, substantially as set forth. 100

In testimony whereof I have hereunto subscribed my name in the presence of two attesting witnesses. 105
